Claims where it may concern

Be it known that I, James G. Gandy, of Lacelle,
in the County of Huddersfield, and State of Massachusetts, have originated
and designed a new Pattern for carpets or other fabrics, of
which the following is a full, clear and exact description, reference
being had to the accompanying drawings, making part of
this specification.

A fourth of a rosette resting on one half of the eight
pointed set figure R, figure R is surrounded by the sprig work C
1122 and 88 are quarters of rosettes, set figures and sprigs
similar to A, B and C.

Four half of a star resting on the ground to said ground
being surrounded by scroll B

47 88 and 99 are quarters of star, ground and scroll similar
to A, B and C.

A rose leaf resting between scroll B and C.

The colors employed for the different portions of the design
may be varied to suit the taste and wish of the manufacturer.

Claim

What I claim as my invention and desire to secure by let-

ter patent is the Design or Pattern for carpets or other fabrics herein
set forth.
